UNITED STATES PATENT OFFICE.

LEON W. ROSENTHAL, OF NEW YORK, N. Y., AND GUSTAVE J. LANG, OF WEEHAWKEN,
NEW JERSEY, ASSIGNORS TO ARTHUR T. MURRAY, OF ALLENTOWN, PENNSYLVANIA.

RENEWABLE FUSE.

1,378,380.

Specification of Letters Patent. Patented May 17, 1921.

Application filed December 24, 1918. Serial No. 268,135.

To all whom it may concern:

Be it known that we, LEON W. ROSENTHAL, a citizen of the United States, residing at 106 Central Park west, in the city, county, and 5 State of New York, and GUSTAVE J. LANG, a citizen of the United States, residing at 849 Boulevard east, Weehawken, in the county of Hudson and State of New Jersey, have invented certain new and useful 10 improvements in Renewable Fuses; and we do hereby declare the following to be a full, clear, and exact description of the invention, such as will enable others skilled in the art to which it appertains to make and use the 15 same.

The present invention relates to renewable fuses of the kind which consists of a permanent fuse holder with terminals for connecting it in an electric circuit and a renewable fuse adapted to be inclosed by the holder and electrically connected in a detachable manner to the terminals thereof. The object of the invention is to provide a permanent and comparatively cheap fuse 20 holder, which, when assembled, gives reliable and permanent contact between it and the inclosed fuse, and at the same time permits rapid renewal of a blownout fuse without the use of special tools.

30 In the accompanying drawings illustrating several embodiments of the invention, Figure 1 is a central longitudinal section of a fuse of the knife blade type; Fig. 2 is a side elevation thereof; Fig. 3 is an end view of the cap; Fig. 4 is a section on line 4-4 of Fig. 1; Fig. 5 is a section on line 5-5 of Fig. 1; Fig. 6 is a side elevation of a ferrule type of fuse; Fig. 7 is a central longitudinal section thereof; Fig. 8 is a section on line 45 8-8 of Fig. 7; and Fig. 9 is a section on line 9-9 of Fig. 7.

In both embodiments illustrated, the cylindrical tube 1 is made or formed of fiber, impregnated paper, or other suitable material, and has in each end a metal end plate 2 with its outer surface substantially flush with the end of the tube. Each of these plates has three depending legs 3 riveted at 4 to the tube.

50 In the knife blade type of fuse shown in Figs. 1 to 5, the fuse 5 extends through the tube substantially parallel to the axis thereof, and through the openings in the end plates. The end portions of the fuse are

turned over the end plates to form fuse terminals 6, one of which extends over the outside of the tube to provide a projecting portion at 7 suitable for an exposed capacity marking thereon.

The metal caps 8 have knife blades 9 riveted or otherwise suitably fastened to form the terminals of the fuse holder for insertion in the spring clips of a panel board. Each end plate 2 has an opening 10 with substantially parallel sides in alignment with the opening in the end plate at the other end of the tube, and has two screw-threaded openings 11 for end screws 12 which extend through the expanding slots 13 of the cap. By making the sides of the openings 10 parallel, no part of either expanding slot registers with the opening in the end plate when the fuse is assembled. In this way the path for the escaping gases upon blow-out of the fuse is made tortuous to provide a muffler effect, and still the end caps may be removed and replaced without entirely removing the screws.

In the ferrule type of fuse shown in Figs. 6 to 9, a central end screw 14 fastens each 80 cap 15 to an end plate 16 and clamps the perforated terminal 17 of the fuse 18 between them. The end plates have openings 19 in alignment with each other, and each opening has divergent side walls. The gas 85 openings 20 in the caps are covered on the inside with gauze 21 or other suitable material.

In both modifications, the tube has a recess 22 extending from its outer end to the open end of the cap, so as to accommodate the projecting end of the fuse terminal in such manner that the cap snugly fits entirely around the tube and prevents the exhaust of the gases of combustion between the tube 95 and caps.

Having thus described our invention what we claim is:

1. A renewable fuse consisting of a tube, end plates fast with said tube and having 100 openings with substantially parallel sides, a fuse passing through the tube and said openings with its ends folded over the outside of the plates to form fuse terminals, caps positioned over the ends of the tube, end screws 105 passing through the caps into screw-threaded engagement with the plates to prevent endwise displacement of the caps on the tube

and to clamp the fuse terminals between the plates and caps, said caps having expanding slots completely out of registry with the openings in the plates to provide a tortuous path for the escaping gases upon blow-out of the fuse.

2. A renewable fuse consisting of a tube, end plates fast with said tube and a fuse passing through the tube and folded over the outside of the plates to form fuse terminals, caps snugly fitting entirely around the outer surface of the tube, and end screws passing through the caps into screw-threaded engagement with the plates to prevent endwise displacement of the caps on the tube and to clamp the fuse terminals between the plates and caps, said plates and caps being provided with staggered openings for the muffled escape of gases.
3. A renewable fuse consisting of a tube,

end plates fast with said tube and having openings with substantially parallel sides, a fuse passing through the tube and said openings with its ends folded over the outside of the plates to form fuse terminals, caps 25 snugly fitting around the outer surface of the tube, and end screws passing through the caps into screw-threaded engagement with the plates to prevent the endwise displacement of the caps on the tube and to 30 clamp the fuse terminals between the plates and case, said caps having expanding slots completely out of registry with the openings in the plates to provide a tortuous path for the escaping gases upon blow-out of the 35 fuse.

In testimony whereof, we hereunto affix our signatures.

LEON W. ROSENTHAL.
GUSTAVE J. LANG.
